UNITED STATES PATENT OFFICE.

CHARLES H. TRUE, OF HAMMOND, INDIANA, AND NEAL TRIMBLE MCKEE, OF DOBBS FERRY, NEW YORK, ASSIGNORS TO LOCOMOTIVE SUPERHEATER COMPANY, OF NEW YORK, N. Y., A CORPORATION OF DELAWARE.

METHOD OF MAKING PIPE-BENDS.

1,169,209.

Specification of Letters Patent. Patented Jan. 25, 1916.

Application filed April 30, 1914. Serial No. 835,360.

To all whom it may concern:

Be it known that we, CHARLES H. TRUE and NEAL TRIMBLE MCKEE, both citizens of the United States, residing, respectively, at 5 Hammond, Indiana, and at Dobbs Ferry, New York, have invented certain new and useful Improvements in Methods of Making Pipe-Bends, of which the following is a specification.

10 Our invention relates to a method of making pipe bends, and particularly to making what are commonly known as U-shaped bends, such as are used in connection with boilers, superheaters and heating apparatus generally and exposed to high temperatures, or when used to carry steam or fluids under pressure.

20 Our invention relates particularly to making bends as aforesaid when the two legs of the bend are required to be very close together.

25 The object of our invention is to provide a method of making a strong and durable bend which can be practised easily, economically and at small expense.

30 A further object of our invention is to provide a method of making a bend as specified in which the internal or free cross-sectional area may be, at all points, fully as great, if not greater, than that of the individual pipes joined by the bend.

35 Still a further object of our invention is to provide a method of making a bend which, when employed as part of a superheater element of a smoke tube superheater, will not unduly restrict the flow of gases through the flue tube but will, on the other hand, facilitate the easy passage of said gases while, at the same time, exerting no greater retarding 40 effect upon the flow of steam through the bend than would be exerted by the same length of the pipe joined by said bend.

45 Various ways of making bends for similar purposes have been proposed, but such ways are attended by certain disadvantages which it is the purpose of our invention to obviate.

50 Our invention will be better understood by referring to the accompanying drawings which show preferred devices for carrying out said invention in which—

Figure 1 represents a plan view of a pair of pipe ends in position on the lower half of the female forming die preparatory to hav-

ing our improved pipe bend formed thereon; Fig. 2 is an end view of Fig. 1 with the 55 upper half of the female forming die in position; Fig. 3 is a view similar to Fig. 1, showing the male forming die in position and the pipes and partially completed pipe bend in section; Fig. 3^a is a section taken 60 along the line 3^a—3^a of Fig. 3, part being broken away; Fig. 4 represents a perspective view of the lower half of the female forming die; Fig. 5 represents a perspective view of the lower half of the forging die; Fig. 6 is 65 a plan view showing the pipe bend, partially completed, lying upon the die of Fig. 5; Fig. 7 is a section along the line 7—7 of Fig. 6 except that the upper member of the forging die is shown in position; Fig. 8 is a view, 70 similar to Fig. 6, showing the pipe bend after the forging dies of Fig. 7 have done their work; Fig. 9 is a section taken along the line 9—9 of Fig. 8; Fig. 10 is a plan view of the completed pipe bend; Fig. 11 is an 75 edge view of Fig. 10; Fig. 12 is a section taken along the line 12—12 of Fig. 10; and Fig. 13 is a section taken along the line 13—13 of Fig. 10.

In the drawings, two pipe lengths 1, 2, 80 which are to be united by a pipe bend, are squared off at one end, as at a and clamped between two similar halves 3, 4 of a female forming die. The lower member 4 of this die is shown in Fig. 4 and comprises a block 85 having parallel semi-circular grooves 5 corresponding to the pipe diameter. The intermediate partition wall or septum between the grooves has one part 6 of the same height as the outer part of the die and another part 90 7 which rises gradually from a minimum height at the end of the die to a maximum height just before it joins the part 6 which it does by gentle curves which are carried around into the grooves 5. Before placing 95 the pipe lengths in the dies 3 and 4, their ends are raised to a welding heat. The dies 3 and 4 must be securely clamped together, and it is best, also, to clamp the pipe lengths outside of the dies and to provide stops (not 100 shown) against which the other ends of the pipe lengths may rest.

The pipe lengths being in position, as above described, a breeches die 8, comprising a pair of tapered legs 9, united by web 10 105 and having slightly pointed ends 11 for easy

insertion, is held by the shank 12 in a suitable press (not shown) and has its legs inserted into the pipe ends at *a* and is pushed home therein. As the web 10 reaches the 5 inner adjacent walls 13 of the pipe ends, its comparatively sharp thin edge 13' will slit said walls and raise and lower the slotted wall portions against the parts 7 belonging to the upper and lower die respectively and 10 compress said slotted portions between the parts 7 and the web 10, which thickens toward its base so as to conform to the varying height of the part 7. If the dimensions of the forming dies and of the breeches die 15 are properly chosen, the upper and lower pair of slotted pipe walls will just properly abut with welding pressure when the edge of the web 10 is distant from the end of the part 6 of the septum lying between grooves 20 5 by substantially the wall thickness of the pipe. A perfect weld will thereby be formed. As will be evident from Fig. 3^a, the web 10 which unites the legs 8 has substantially the same shape as that of the 25 space comprised between the parts 7 and uniting the bores of the female forming die; but this web is smaller in section than said space and is everywhere separated from the parts 7 by an amount substantially equal 30 to the wall thickness of the pipes. This separating distance might, however, if desired, be greater at one point and less at another within the scope of the invention, the prime requisite being that the separating 35 space must just take and contain the slotted and spread pipe walls so as to bring their edges together with the necessary pressure to effect a satisfactory weld. The breeches dies is then withdrawn, the forming die 40 opened, and the pipe lengths with the partially completed bend removed. At this stage in the operation, the pipe bend will have the appearance shown in Figs. 6 and 7, that is to say, the two pipes will be parallel 45 to one another, and will retain their original shape at their ends, except in the connecting region or yoke between them formed by the slotted parts of the pipe walls, which have been raised and lowered respectively and 50 welded together as aforesaid. It will now be necessary to suitably close the ends of the partially completed bend and at the same time to give said bend a suitable shape. These two operations may be carried out simultaneously as follows: The forging die 15, comprising similar members, is used in any suitable forging machine (not shown) after the manner shown in Fig. 7. The preferred 55 form of the two similar members of this forging die is indicated in Fig. 5 where the one part 16 is scooped out to correspond with the conformation of the completed bend, while another part 17 is recessed by an amount substantially equal to the thickness 60 of the pipe wall. A central recess 18 is

provided at one end to receive a slip die 19 which is inserted centrally into the partially formed bend as shown in Fig. 6. With the inchoate pipe bend in position, as shown in Figs. 6 and 7, the forging dies are lightly 70 operated so as to effect a preliminary shaping. As soon as the central portion of the bend is flattened sufficiently to bind upon the slip die, the latter is withdrawn. The forging operation is then continued until the bend 75 has assumed the appearance shown in Figs. 8 and 9 where, so far as its form is concerned, it is complete except for the fin 21 resulting from the flattening of the surplus wall portions lying outside of the curve 80 which is to form the outer boundary of the completed bend. The small opening left at the end of the die by the withdrawal of the slip die should have been closed by any suitable means before the completion of the de- 85 scribed forging operation although, if preferred, it may be closed after the remainder of the forging operation has been completed. Or, after the slip die has been removed we may remove the incomplete pipe bend, as it 90 thus exists, to a second pair of forging dies similar to those just described but having no recess 18 for the slip die. This second pair of dies will thus close the slip die opening as well as the remainder of the pipe bend 95 opening. It now remains to remove this fin 21 and this, we find can be most easily done by using an oxy-acetylene burner and running around the pipe end at the line of its junction with the fin so as to cut the fin 100 away. By then again running the flame around the curved end while projecting it into the plane of separation of the edges, the latter will be welded together in a firm and durable weld. Or the fin may be cut off 105 by shearing in a suitable trimming press, or the equivalent, before proceeding to weld the edges together.

Instead of proceeding from the incomplete bend of Fig. 6 through the form of Figs. 8 and 9, *i. e.*, instead of first compressing the ends so as to form the fin 21, and then cutting off said fin and welding the edges together, as just described, we may, if we prefer, first shear off all that portion of 115 the incomplete bend (Fig. 6) which lies between the extreme ends and the curved line *b*. The edges at said line *b* may then be brought together by suitable forging dies, or by other suitable means, and then welded 120 together by the oxy-acetylene flame as before.

Other methods of bringing the edges (at the curve *b*) together or of welding them durably when brought together, may be employed within the spirit of our invention.

By suitably shaping the forming dies the end *c* of our improved pipe bend may be formed as a sharp edge from which the bend gradually widens until it has the full 130

thickness of the pipes proper when pipes and bend merge into one another.

The bend is not quite so thick through the yoke 14 as at the sides thereof, in the particular form of bend which has been described, this lessened thickness resulting, in effect, in the production of a central groove on each side of the bend. The fire gases, as they reach the end *c* of the bend, are split 10 and divide and pass on past the bend, the two grooves facilitating the passage of the gases and, at the same time, providing a larger heating surface for the gases to contact with. This groove is, however, not essential to the practice of our invention and may be omitted. Indeed, the form and proportions of the bend may be varied widely without departing from the spirit of the invention and the section through the bend 15 (as shown in Fig. 13) may have any desired and convenient form.

The cross-sectional area of the passage through the pipe bend, at all points thereof, can obviously be fully as great as that of the 20 pipe itself, and as much greater as may be desired. This is accomplished by choosing a suitable length and thickness for the web 10 and by correspondingly dimensioning the forming dies with which the web must co- 25 operate.

When the pipe bend, made as above described, is completed (Figs. 10-12) it is practically impossible to find the welds, so perfectly and smoothly are the edges united. 30 In particular, there will be no fins projecting inwardly from the welds; such fins occur in certain other methods of pipe bend manufacture and are very difficult if not impossible to remove. If left in place such 35 fins will restrict the passage and produce a lack of uniformity among different bends as well as inefficiency in individual bends.

The slip die, while preferred by us, is not essential to the practice of our invention. 40

Changes in the exact form of the various dies, and in the details of the operations employed in shaping the bends and making the welds, may be made within the spirit of 45 our invention as defined in the following claims:—

1. The method of making pipe bends which comprises taking two pipes and slitting the wall of each longitudinally for a 50 suitable distance from the pipe end, pressing the pipe walls on each side of said slits outwardly, causing the edges of the two slit- 55 ted parts of one pipe to abut against corresponding edges of the other pipe and then welding said edges together, and finally

closing the end of the incomplete bend thus formed.

2. The method of making pipe bends which comprises taking two pipes and slitting the wall of each longitudinally for a 60 suitable distance from the pipe end, pressing the pipe walls on each side of said slits outwardly, pressing the edges of the two slit- 65 ted parts of one pipe forcibly against corresponding edges of the other pipe while 70 said edges are at welding heat thereby causing them to be united, and finally closing the end of the incomplete bend thus formed.

3. The method of making pipe bends which comprises holding two pipe lengths 75 to be joined in the relative position they are to occupy when the bend is completed, simultaneously slitting neighboring walls of both pipes for a suitable distance from the ends of said pipes and at the same time 80 pressing the slit parts outwardly until they abut in pairs, welding said abutting edges together, and finally closing the end of the incomplete bend thus formed.

4. The method of making pipe bends 85 which comprises holding two pipe lengths to be joined in the relative position they are to occupy when the bend is completed, simultaneously slitting the juxtaposed walls of both pipes in the axial plane common to 90 said pipes and for a suitable distance from the ends of the pipes and simultaneously pressing the slit parts outwardly until they abut in pairs, welding said abutting edges together, and finally closing the end 95 of the incomplete bend thus formed.

5. The method of making pipe bends which comprises holding two pipe lengths to be joined in the relative position they are to occupy when the bend is completed and 100 with their ends at welding heat, slitting neighboring walls of both pipes for a suitable distance from said ends, pressing the pipe walls on each side of each slit outwardly until said edges are abutted forcibly 105 together in pairs thereby uniting them by a weld, and finally closing the end of the incomplete bend thus formed.

In testimony whereof we have hereunto set our hands in the presence of two subscribing 110 witnesses.
